BOX WITH SLIDING LATCH

Fred Frederics, New York, N. Y.

Application April 13, 1946, Serial No. 661,982

1 Claim. (Cl. 206—1.5)

1

The present invention relates to boxes for holding bottles of perfume, cosmetic packages and various other articles.

An object of this invention is to provide a novel and improved box structure having a hinged top and locking means therefor.

A further object hereof is to provide a novel and improved box having a hinged top and also a locking means therefor, which may be used to serve as the applicator of perfume or cosmetic material housed within the box.

Another object of this invention is to provide a novel and improved box of the character mentioned, whose locking means is both decorative and otherwise useful.

Another object hereof is to provide an article of the kind described, which is beautiful in appearance, reasonably cheap to manufacture, easy to use, and efficient in carrying out the purposes for which it is designed.

Other objects and advantages will become apparent as this disclosure proceeds.

In the accompanying drawings forming part of this application, similar characters of reference indicate corresponding parts in all the views.

Fig. 1 is a perspective view of a box structure shown in open condition and constructed in accordance with the teachings of this invention. A component used to lock the box, is here not shown.

Fig. 2 is a perspective view showing such component.

Fig. 3 is a perspective view showing said box structure in closed and locked condition.

Fig. 4 is a section taken at line 4—4 in Fig. 3.

In the drawings, the box structure indicated generally by the numeral 15, consists of an upright lower box 16, and an inverted upper box 17 positioned atop member 16, in rim to rim contact relation and both hingedly associated at the rear of the structure about a horizontal axis 18; member 17, thus serving as the cover for the box structure 15.

Interior the box member 16, a channel member 19 carried therein, forms with the front wall 16', a substantially upright chute 20, which is closed at its bottom by an element 21, which is like a step extending inwardly into the box structure, laterally from said front wall 16'. Said chute 20, is open at its top which commences at the rim of box member 16.

Interior the box member 17, a channel member 22 carried therein, forms with the front wall 17', a substantially upright chute 23, which is closed

2

at its top by 24. Said chute 23 is open at its bottom which commences at the rim of the box member 17. Both chutes 20 and 23 are in alignment when the box structure 15 is closed.

A locking member designated generally by the numeral 25, adapted to be positioned within said chutes, is viewable and accessible from the front of the box structure 15, through slot or opening 26 in front wall 16', and through slot or opening 27 in wall 17' of the cover member 17.

The upper portion 25' of the locking member 25, is adaptable to be slidably positioned along chute 23, while when the box structure is closed after said locking member is so positioned, its

bottom portion 25'' will enter opening 26; dimensions of the parts being such as to so permit, as well as to afford upward movement of the locking member through distance "A." When the box structure with associated locking member 25 therein is so closed, said locking member 25, by its own weight will fall so that the lower end thereof shall enter slot 21' in step 21, whereby the box is locked. To open, said member 25 is slid upwardly until it is free of engagement in said slot 21', whereupon members 15 and 16 are free for movement with respect to each other about their hinge connection 18.

Said locking member 25 may assume any decorative form, as for instance that of an arrow as illustrated, which carries a corking member 28, whereby said member might also be used as a stopper for bottle 29 ordinarily housed in said box structure 15, and if desired as an applicator of its contents.

This invention is capable of numerous forms and various applications without departing from the essential features herein disclosed. It is therefore intended and desired that the particular description herein be deemed illustrative and not restrictive and that the patent shall cover all patentable novelty herein set forth; reference being had to the following claim rather than to the specific embodiment herein to indicate the scope of this invention.

45 I claim:

In an article of the character described, a lower upright receptacle, an upper inverted receptacle; said receptacles being positioned in rim to rim contact relation forming a closed box structure and hingedly associated at their respective rears whereby the upper receptacle serves as a swingable cover for the lower receptacle, a track means carried on the front wall of the upper receptacle, adapted to permit up and down slidable movement therealong, an element carried later-

ally by the front wall of the lower receptacle having an opening; both receptacles being formed with longitudinal rearwardly extending channels; both said channels being continuous when the box structure is closed; the track means being part of the channel associated with the upper receptacle and the element mentioned being positioned across the channel associated with the lower receptacle; said channels being open along the front of the box structure, and a separate locking member being substantially housed within said channels when mounted to lock the box, the upper portion of said locking member being adapted to be removably slidably received in said track means only when said receptacles are 15 swung apart, and when so mounted, said locking

member being adapted, when the box structure is closed and upon then being slid downwardly along and in engagement with the track means, to enter said opening and be engaged by said 5 element, whereby the box structure is locked.

FRED FREDERICKS.
